UNITED STATES PATENT OFFICE.

ALBERT H. SISSON, OF CHICAGO, ILLINOIS, ASSIGNOR TO FORSYTH BROTHERS COMPANY, OF CHICAGO, ILLINOIS, A CORPORATION OF ILLINOIS.

CAR CONSTRUCTION.

1,112,858.

Specification of Letters Patent.

Patented Oct. 6, 1914.

Original application filed October 12, 1911, Serial No. 654,308. Divided and this application filed July 18, 1913. Serial No. 779,676.

To all whom it may concern:

Be it known that I, ALBERT H. SISSON, a citizen of the United States, residing at Chicago, in the county of Cook and State 5 of Illinois, have invented certain new and useful Improvements in Car Construction, of which the following is a specification.

My invention relates to car construction and refers particularly to an improved type 10 of car frame and sheathing used in connection therewith.

This application is a division, in compliance with requirements of the Patent Office, of my copending application Serial 15 No. 654,308, for car construction, filed October 12, 1911.

I have found that it is particularly advantageous in order to obtain a car of light and strong construction to employ supporting members which are suitably disposed on the sides of the car. The supporting members may consist of plates or sheathing formed so as to have the function of a supporting framework. When 25 the sheathing is formed in this manner, reinforcing angle irons or the like may be used in conjunction with the supporting portions of the sheathing.

A further advantage of my invention 30 consists in the manner of forming the upper portion of the sheathing, the lower portion of the sheathing and the car post. These members may be formed in one or more pieces. The formations are of such a character as to permit the use of exceptionally 35 light material, while affording the maximum strength.

These and other advantages of my invention will be more readily understood 40 by reference to the accompanying drawing, which shows in side elevation and by way of illustration, one embodiment of my invention.

Having reference to the drawing, the 45 car is shown as having a roof 10 and a plurality of side sheathing plates 11. These sheathing plates are formed with the diagonally disposed truss members 12 and the vertical members 13. Between the vertical 50 members 13 and the diagonal truss members 12 are formed the panels 14. If so desired

a window 15, a door 16, or the like, may be formed between the vertical members 13, 13. The diagonal truss members 12 are preferably reinforced by suitable angle 55 irons or the like 17, and inside of the vertical members 13 may be located the car posts 18 to which the sheathing plates are secured.

It will be apparent to those skilled in the 60 art that many changes could be made in the detailed construction of the parts which I have described without departing from the spirit or scope of my invention.

I claim:

1. In a car construction, the combination of a sheathing covering the side of the car and having obliquely and vertically disposed strengthening members and having window openings between said members, 70 substantially as described.

2. In a car construction, the combination of a sheathing covering the side of the car and having obliquely and vertically disposed strengthening members formed 75 therein and having window openings between said members, substantially as described.

3. In a car construction, a sheet metal sheathing composed of integral unit sections of substantially I-shape, the upper and lower horizontal members forming portions respectively of the sheathing above and below contiguous window openings and the vertical portion separating the 85 window openings, substantially as described.

4. In a car construction, a side sheathing composed of unit sections each comprising two horizontal portions integrally joined 90 by a vertical portion, the space between the horizontal portions on the two sides of the vertical portion forming adjacent halves of contiguous window openings, substantially as described.

5. In a car construction, a side sheathing composed of a plurality of unit sections each comprising two horizontal portions integrally joined by a vertical portion, the horizontal portions respectively forming 100 sections of the side sheathing beneath adjacent halves of contiguous window open-

65

ings and the vertical portion forming a window post section separating adjacent window openings, the said units paneled to form between the panels obliquely disposed integral strengthening members, substantially as described.

In testimony, whereof I have hereunto

signed my name in the presence of two witnesses.

ALBERT H. SISSON.
